Patented Feb. 13, 1968

210,170

ROTARY SLIDE TRAY

Grant D. Ross, Jr., Deerfield, Ill., assignor to Bell
& Howell Company, Chicago, Ill., a corporation
of Illinois

Filed Mar. 4, 1966, Ser. No. 1,285

Term of patent 14 years

(Cl. D61—1)

Fig. 3.

Fig. 4.

FIG. 1 is a front elevational view of a rotary slide tray showing my new design;

FIG. 2 is a side elevational view, the opposite side being substantially a mirror image thereof;

FIG. 3 is a rear elevational view; and

FIG. 4 is a bottom plan view thereof.

I claim:

The ornamental design for a rotary slide tray, as shown and described.
